UNITED STATES PATENT OFFICE.

HAL DICKINSON, OF MINNEAPOLIS, MINNESOTA, ASSIGNOR TO DUPLEX ART SIGN COMPANY, OF MINNEAPOLIS, MINNESOTA, A COPARTNERSHIP CONSISTING OF HAL DICKINSON, INEZ IDA DEAKIN, AND GEORGE S. STINSON.

DESIGN FOR A SIGN.

Application filed October 15, 1927. Serial No. 23,756. Term of patent 3½ years.

To all whom it may concern:

Be it known that I, HAL DICKINSON, a citizen of the United States, residing at Minneapolis, in the county of Hennepin and State of Minnesota, have invented a new, original, and ornamental Design for a Sign, of which the following is a specification, reference being had to the accompanying drawing, forming part thereof.

Fig. 1 is a perspective view of a sign showing my new design; and Fig. 2 is an edge elevation of the same.

I claim:

The ornamental design for a sign, as shown.

HAL DICKINSON.
